UNITED STATES PATENT OFFICE

1,998,335

AUTOMATIC SERIES CUT-OUT SWITCH

Joseph L. Shea, Nashua, N. H., assignor to General Electric Company, a corporation of New York

Application April 12, 1933, Serial No. 665,696

3 Claims. (Cl. 175—294)

My invention relates to automatic series cut-out switches and more particularly to automatically operated series cut-out switches for isolating a section of a series circuit when a break occurs therein.

The automatically operated series cut-out switches heretofore used have been operated by a coil energized by current from the main circuit. These switches are maintained in the open position as long as the coil is energized. If, however, the coil becomes deenergized, the cut-out switch closes and connects the ends of the broken circuit to the main circuit. This is dangerous to any one coming in contact with the conductors of the broken circuit.

It is the principal object of my invention to provide a series cut-out switch, which will open in response to a break in the section of the circuit which is to be isolated, and to maintain the cut-out switch open independently of current in its operating coil or independently of the current in the main circuit.

The novel features which I believe to be characteristic of my invention are pointed out in the appended claims. My invention itself, however, will be best understood by reference to the accompanying drawing in which Fig. 1 illustrates diagrammatically a loop circuit, containing a relatively few lamps, connected in series with a main circuit by a series cut-out switch built in accordance with my invention, and Fig. 2 illustrates the same circuit disconnected and the cut-out switch in its open position.

Referring to the drawing in detail, the main circuit is represented by conductors 10 and 11. A circuit including conductors 12 and 13 and a relatively few lamps 14, which may be referred to as the loop circuit, is arranged to be connected into the main circuit through cooperating contacts in the cut-out switch.

The cut-out switch includes an arm 16 made of insulating material and has attached to its respective ends contacts 17, 18, 19 and 20. The contacts 17 and 18 are attached to one end of the arm and are connected to the main line conductor 10. The contacts 19 and 20 are attached to the other end of the arm 16 and are connected to the main line conductor 11. The arm 16 is mounted on a shaft 22 which is arranged to hold the arm 16 in an up or down position and move the bar from one to the other of these two positions.

When the arm 16 is in the up position the contacts 17 and 18 engage respectively contacts 23 and 24, which are connected to the conductors

12 and 13. In this position of the arm 16 the conductors 10 and 12 are connected to each other through contacts 17 and 23 and the conductors 11 and 13 are connected to each other through contacts 19 and 24 whereby the loop circuit and the main circuit are connected in series with each other.

When the arm 16 is in the down position the contacts 18 and 20 engage respectively contacts 26 and 27 which are connected to each other through conductor 28. If, therefore, the arm 16 is in the down position the conductors 10 and 11 are connected to each other through contacts 18, 20, 26 and 27 and conductor 28; the contacts 23 and 24 being isolated from the main circuit.

The operating shaft 22, for the arm 16, is mounted for vertical movement in guide bearings 29 and 30 and is pivotally connected, by a pin 32 to an actuating bar 33. The bar 33 is in turn pivoted to fixed support 35 and is moved vertically by toggle links 36, 37, 38 and 39. Link 36 is pivotally attached to the bar 33, the link 37 is pivotally attached to a fixed support 40 and the link 38 is pivotally attached to the two links 36 and 37 at their common pivot pin 34. The links 38 and 39 may be locked into position to exert a thrust against the pin 34 and thereby lift the arm 16 to its upper position. The thrust toggle is operated by a handle 41 through levers 42 and 43 and shaft 44; the shaft 44 being mounted for rotation in bearings 46 and 47. As shown in Fig. 1, therefore, the arm 16 is maintained in its upper position by toggles 36—37 and 38—39, levers 42 and 43, shaft 44 and a spring 48 which is connected between a fixed support 49 and lever 42. In order to collapse the thrust toggle 38—39 and permit a spring 50 acting between bearing 29 and bar 16 to force arm 16 downward, so that contacts 18 and 20 engage contacts 26 and 27, a pin 51 operated by an armature 52 of a coil 53 is provided.

In accordance with my invention the coil 53 is energized upon occurrence of a break in the loop circuit by current flowing across a spark gap and when the coil has operated to collapse the toggles, the arm 16 is moved down by the action of spring 50, to close the gap in the main circuit and to simultaneously shunt the coil 53. It is maintained in this position until reset by movement of handle 41 as will hereinafter be explained. In this manner the loop circuit remains isolated from the main circuit independently of the current in the coil 53 and independently of the current in the main circuit.

As stated above, the tripping coil is connected

across the gap in the main circuit in multiple with the loop circuit and in series with a pair of spaced electrodes. The circuit may be traced from conductor 10 to conductor 54, coil 53, conductor 55, electrode base 56, electrode arm 57 and electrode 58, electrode 59, conductor 60. Electrode 58 is spaced from electrode 59 a distance such that when a break occurs in the loop circuit an arc will easily start across the space between the two electrodes and will flow through electrode 59 and conductor 60 to conductors 11, the other side of the line. The coil 53 is, therefore, in series with the gap between electrodes 58 and 59, and when the line potential builds up across these two electrodes the coil 53 is energized by the current flowing across this gap. A second pair of electrodes 61 and 62 is provided for use while resetting the cut-out, as will hereinafter be explained.

After the switch has been tripped automatically, it may be reset by pushing handle 41 upwards against the force of spring 48. The lever arm 42, shaft 44 and lever arm 43 are thereby rotated clockwise and the links 38 and 39 are straightened with respect to each other until they are locked into thrusting position. The handle 41 is then pulled down. The locked toggle 38-39 is pushed forward by lever 43 against the knee of the toggle 36-37 and the arm 16 is lifted until the contacts 17 and 19 engage respectively the contacts 23 and 24. When the handle 41 is pulled down to the limit of its movement as determined by the adjustable stop 63 mounted on shaft 44, the parts are in such relation that the pull of the spring 48 on lever 42 is sufficient to hold the arm 16 in its upper position.

The action of the cut-out is clearly shown in a simplified manner in Fig. 2. When a break occurs in the loop circuit, due to a burned-out lamp 14 for example, current will flow from the conductor 11 through conductor 60 to electrode 59. As explained above, this electrode is so spaced from the electrode 58 that when the line potential builds up across them, after the loop circuit is broken, an arc will be established across this gap and current will flow to electrode 58, conductor 55, coil 53, conductor 54 to conductor 10, the other main line conductor. As soon as current flows in the coil 53, the pin 51 is raised and breaks the toggle 38-39 and arm 16 is forced down by spring 50. The coil circuit is shunted and the main circuit is closed as soon as the arm 16 reaches its down position. Then in order to reset or reclose the cut-out switch the handle 41 is raised to turn the shaft 44 clockwise.

A second pair of electrodes 61 and 62 is provided for establishing a shunt circuit about the contacts 17 and 19 while they are being moved into contact with the loop circuit contacts 23 and 24. This shunt is established with the aid of a lever 64 mounted on shaft 44. An insulating member 65 is attached to this lever 64 and engages the electrode arms 57 and 66 when the cut-out is in the closed position. The electrode arms are thereby turned about their respective pivots in the base 56 and the electrodes are spaced a predetermined distance from each other. When

the handle 41 is pushed upward, however, to straighten the toggle 38-39, the member 65 is raised and the electrodes are forced into engagement with each other by a spring 67, thus establishing the shunt circuit around the contacts 17 and 19. This shunt circuit may be traced from conductor 11 to conductor 60, electrodes 59 and 58, electrode arm 57, base 56, arm 66, electrodes 61 and 62 to conductor 10. This shunt circuit, therefore, insures the transfer of connections while no current is flowing through the contacts.

I have thus provided a practical series cut-out which operates positively to separate a loop circuit from a main circuit and which will maintain this separation of the circuits independently of the current in the operating coil and independently of the current in the main circuit.

What I claim as new and desire to secure by Letters Patent of the United States, is:—

1. A cut-out switch including a pair of stationary contacts connected respectively to the ends of a loop circuit, a second pair of stationary contacts connected to each other, a pair of movable contacts connected to a main circuit and arranged for movement between said pairs of stationary contacts, a toggle mechanism arranged to hold said movable contacts in engagement with said loop circuit contacts, a pair of spaced electrodes and a trip coil connected across the movable contacts in series with each other so as to receive current from said main circuit when said loop circuit breaks, and means responsive to the energization of said coil for tripping said toggle mechanism whereby the loop and said trip coil are disconnected from the main circuit and said movable contacts engage said second pair of stationary contacts.

2. A cut-out switch including a pair of stationary contacts connected respectively to the ends of a loop circuit, a second pair of stationary contacts connected to each other, a pair of movable contacts connected to a main circuit and arranged to engage respectively said stationary contacts, a toggle mechanism arranged to hold said movable contacts in engagement with said loop circuit contacts, a pair of spaced electrodes and a coil connected in series with each other and in multiple with said movable contacts arranged to trip said toggle mechanism when energized, and means for maintaining said movable contacts in engagement with said second pair of stationary contacts when said toggle is tripped.

3. In combination, a loop circuit, a main circuit, a cut-out device arranged to connect said loop circuit in series with said main circuit, a trip coil, means connected in series with said trip coil and arranged to pass current from said main circuit to said coil in shunt to said loop circuit when said loop circuit breaks, means responsive to the energization of said trip coil for disconnecting said loop circuit from said main circuit, means for closing the gap in said main circuit simultaneously with the disconnection of said loop circuit from said main circuit, and means independent of the current in said main circuit for maintaining said circuit disconnected.

JOSEPH L. SHEA.
